UNITED STATES PATENT OFFICE.

ARTHUR F. BRIDGE, OF LOS ANGELES, CALIFORNIA, ASSIGNOR OF ONE-FOURTH TO MORETON R. THOMPSON AND ONE-FOURTH TO FRANKLIN S. WADE, BOTH OF LOS ANGELES, CALIFORNIA.

GAS HOLDER.

Application filed December 7, 1921. Serial No. 520,533.

To all whom it may concern:

Be it known that I, ARTHUR F. BRIDGE, a citizen of the United States, residing at Los Angeles, in the county of Los Angeles, 5 State of California, have invented certain new and useful Improvements in Gas Holders, of which the following is a specification.

This invention relates to gas holders of the general type referred to in my Letters 10 Patent No. 1,426,145, issued August 15th, 1922, for gas holders. In said patent I explain a type of holder wherein the gas, upon being pumped into the gas chamber, displaces water therefrom into an upper 15 chamber through a connecting pipe that opens into the lower chamber near its bottom. In such an arrangement the two chambers are of substantially equal size, the upper chamber being large enough to hold 20 all of the water which, when the gas holder is empty, completely fills the lower chamber.

The present invention has to do with improvements upon the gas holder shown in said copending application; and the general 25 object of the present invention is to reduce the total size of the gas holders, in proportion to its gas capacity. In the device of said copending application the holder must be of a total capacity (both for gas 30 and water) approximately twice the capacity for gas. In accordance with the present invention I provide, instead of a single gas chamber, a plurality of gas chambers, and provide but a single water chamber for all 35 the gas chambers; so that, by making a gas holder with say, three gas chambers and one water chamber, it is only necessary to have a water chamber that is approximately one-quarter, or a little more, the size of the 40 complete holder. Of course, by increasing the number of gas chambers further, even this proportion may be reduced. Theoretically, there is no limit to the number of chambers into which any given holder may 45 be subdivided, and therefore no theoretical limit to the number of gas chambers that may be served by one water chamber; but, of course, in practice there is a most economical number of gas chambers which may 50 be used.

The broad feature of the invention—that is of using a plurality of gas chambers with a single water chamber—is susceptible of use in two different manners. For instance, gas may be stored in the several

chambers at different pressures, or may be stored in them at equal pressures. The form of device in which the gas is stored in the different chambers at different pressures is the specific subject-matter of this application; while the form of device in which the gas is stored in the different chambers at equal pressures is the specific subject-matter of another copending application, Serial No. 520,534, and filed on even date herewith. 60 The broader claims that cover subject-matter common to these two applications are contained in this present application.

The invention will now be best understood from the following detailed description of 70 a preferred specific form of apparatus that embodies the invention, reference for this purpose being had to the accompanying drawings, in which—

The single figure is a diagrammatic view 75 in vertical section illustrating the holder and its charging and discharging system.

It will be understood of course that in the accompanying drawings, and in this specification, I explain only the simple elements of the holder; it being unnecessary to enter into details as to construction of the walls and partitions of the holder, and their staying or supporting against pressure, or to enter into details of construction of valves 85 and regulators, as such details may be supplied by those skilled in the art.

In the drawing I show a suitable tank structure, say a tank constructed of steel. The details of this construction need not 90 here be illustrated or described. This tank structure is divided by partitions 10, 11 and 12 into three gas holding chambers 13, 14 and 15, and one water holding chamber 16. The partitions may be braced or stayed in 95 any suitable manner, not necessary to illustrate herein. It will be understood that the holder may be divided into any suitable manner of gas chambers, not necessarily being limited to the number shown. Communication for the passage of water from one chamber to the next is provided by suitable pipes communicating with the bottoms of the respective chamber; and this may be preferably provided by pipes 17, 17^a and 17^b 100 inside the chambers in communication at their bottoms with the bottom of one chamber and in communication with the chamber immediately above. A gas line 18 communicates with the top of chamber 13, a gas 105 line 19 with the top of chamber 14, and a gas line 20 with the top of chamber 15. A gas line 21 110

line 19 with the top of chamber 14, and a gas line 20 with the top of chamber 15. Gas line 18 connects directly to pipe 21 which is the one through which gas is put into the gas holder, this pipe being provided with a check valve 22 and a pressure regulator R^1 . The gas delivery pipe is indicated at 23 (provided with a check valve 24 and a pressure regulator R^2); and pipe 18 communicates with outlet pipe 23 through a check valve 24 and back pressure regulator R^3 . Pipe 19 also similarly communicates with pipe 23 through a check valve 25 and back pressure regulator R^4 ; while pipe 20 communicates with outlet pipe 23 through a check valve 26; it not being necessary that the pipe 20 have a back pressure regulator. Regulator R^2 is set to take off gas down to the minimum pressure produced by the minimum water head and to deliver the gas at the required constant distribution pressure.

In using a gas holder of this type, water is first put into the holder in sufficient quantity to completely fill the lower chamber 13 and fill enough of the next chamber 14, sufficient to maintain a head above the partition 10, equal to the minimum pressure at which it is desired to withdraw the last quantity of gas from each one of the chambers. Thus, the holder carries somewhat more water than the capacity of each one of the gas chambers, and the water chamber 16, to hold this water, must be made somewhat larger than each one of the gas chambers. Gas is fed into the holder through the pipes 21 and 18, the gas passing into the upper part of chamber 13, displacing the water, and pressing it up through pipe 17 into chamber 14. This goes on until chamber 13 is full of gas at a pressure equal to the head of water on the chamber, the water level then standing approximately at the line designated L^1 in chamber 15. Then the gas begins to bubble up through the water that remains standing in the lower pipe 17; and bubbles up through the body of water which then fills chamber 14, gradually displaces that water, forcing it down and forcing it out and upwardly through the pipe 17^a up into chamber 15. When this chamber has been completely filled with gas, then the water level stands as indicated at L^2 , and then the gas begins bubbling up through the water standing in pipe 17^a and chamber 15 is then filled, displacing the water completely up into water chamber 16, the pipe 17^b then remaining full of water. When the holder is full of gas, the pressure on upper gas chamber 15 is of course equal to the head of water between the level L^2 and the bottom of pipe 17^b. The pressure of gas in chamber 14 is greater than that on the gas in chamber 15, the difference being the head of water standing in pipe 17^a; likewise the pressure on the gas in lowermost

chamber 13 is greater than that in chamber 14, the difference being represented by the column of water in pipe 17. It will be noted that, as the filling of the holder goes on, the pressure on the gas in each one of the lower chambers increases up to the maximum. For instance, as the water is forced higher and higher, the pressure on the gas in chamber 13 increases. Gas is fed to the holder under a pressure sufficient to fill the holder at such maximum pressure.

Now, in discharging the holder, the pressure regulator R^2 is set to take off gas at the minimum pressure; and this minimum pressure is a pressure which stands on the gas in any one chamber at the time the last of the gas is being taken out of that chamber. For instance, that minimum pressure is the pressure which is on the gas in chamber 15 at the time the water level has fallen approximately to the level indicated at L^2 in chamber 16, and the last of the gas is being taken out of compartment 15. That pressure is the hydrostatic head of the water at level L^2 above partition 12.

The regulators at R^3 and R^4 are back-pressure regulators; and R^4 is set only to open when the pressure in pipe 19 has fallen to that produced by the static head on chamber 14 with the water level at L^2 ; and R^3 is set likewise to open when the water level reaches L^1 . Consequently, the first withdrawal of gas will of course be from chamber 15. This withdrawal of gas will go on until all of the gas is withdrawn from chamber 15; and at the same time, the pressure on chambers 14 and 13 being reduced by the fall of the head of water over them, a certain amount of gas will bubble up through the pipes 17 and 17^a into chamber 15 to be withdrawn through the pipe 20. As soon as the pressure in pipe 23 has fallen to the predetermined pressure, then back pressure regulator R^4 opens and gas will commence to pass out through pipe 19 from chamber 14; and will continue to do so until all of the gas has been withdrawn from chamber 14 and a certain amount of gas has bubbled up through pipe 17 from the chamber 13, as the pressure on gas in chamber 13 is reduced by the fall of water head above it. Then the back pressure regulator R^3 will open and gas will then be withdrawn from the chamber 13 until all the gas is taken out and the water has fallen to the level L .

In order to get rid of the air that stands above the water level in the two chambers 14 and 15, air outlet valves are provided at A^1 and A^2 , these valves being controlled by floats F^1 and F^2 , at the upper ends of the standpipes 17^a and 17^b. The air valves communicate with the two chambers 14 and 15 at their tops; and the floats F^1 and F^2 are set at or near the tops of the chambers, so that the floats will keep the air valves A^1 and A^2 open.

and A² open at all times except when the water level is at or above the respective floats. For instance, as chamber 13 is being filled with gas and the water level in chamber 14 is being raised, the valve A¹ will be open until the water level reaches approximately the top of the chamber; and then float F¹ will rise, closing the valve A¹, before gas begins to bubble up into chamber 14. 10 Similar action takes place as the water level rises in chamber 15. Reversely, when the holder is being emptied, as soon as the level falls to or below these respective floats, their respective air valves will be opened to allow 15 air to enter the chambers to relieve the partial vacuum that would otherwise be formed.

It will be seen from this description that one body of water serves a number of gas chambers. Consequently the size and cost 20 of a holder for holding any given quantity of gas is very greatly reduced, as the capacity of the water chamber needs only be a fraction of the capacity of the gas chamber. This, feature, of a single water body, is the 25 primary feature of this invention, and it will be understood that my description here is only a typical form of apparatus embodying the invention; and that the invention is not to be restricted to the details herein set forth except as specifically so stated in the 30 following claims. For various modifications may be made; for instance, the arrangement of piping and valves may be easily modified and still accomplish the same results.

35 Having described a preferred form of my invention, I claim:

1. A gas holder of the water displacement type, characterized by a plurality of gas chambers and a water chamber, each chamber 40 having water passage communication leading from the bottom of one to the bottom of another chamber.

2. A gas holder of the water displacement type, characterized by a plurality of gas 45 chambers and a water chamber, each chamber having water passage communication leading from the bottom of one to the bottom of another chamber, the water chamber being above all the gas chambers.

3. A gas holder of the water displacement 50 type, characterized by a plurality of gas chambers and a water chamber, the gas chambers being arranged at successively higher levels and the water chamber at a level above the highest gas chamber, each except one of the gas chambers having water 55 passage communication from its bottom to the bottom of the gas chamber next above, and said above excepted chamber having water passage communication from its bottom to the bottom of the water chamber. 60

4. The device of claim 3, further characterized by a gas inlet communicating with the lowermost gas chamber and a gas outlet communicating with each chamber. 65

5. A gas holder of the water displacement 70 type, characterized by a plurality of gas chambers and a water chamber, each chamber having water passage communication leading from the bottom of one to the bottom of another chamber; an atmospheric communication at the tops of some of the gas chambers, and means operable by virtue of the changing water level in those chambers to open and close the communication. 75

6. A gas holder of the water displacement 80 type, characterized by a plurality of gas chambers and a water chamber, the gas chambers being arranged at successively higher levels and the water chamber at a level above the highest gas chamber, each except one of the gas chambers having water 85 passage communication from its bottom to the bottom of the gas chamber next above, and said above excepted chamber having water passage communication from its bottom to the bottom of the water chamber; an atmospheric communication in each of the gas chambers except the lowermost chamber, and means operable by virtue of the changing water level in those chambers to open and close the communication. 90

In witness that I claim the foregoing I have hereunto subscribed my name this 30th day of November 1921.

ARTHUR F. BRIDGE.

Witness:

VIRGINIA BERNINGER.
